CLAIM

The ornamental design for automobile tire, as shown and described.

DESCRIPTION

FIG. 1 is a front view of an automobile tire, showing the new design, a rear view thereof, a top plan view thereof, a bottom plan view thereof appearing the same as the front view; FIG. 2 is a right side view of the automobile tire, a left side view thereof appearing the same as the right side view; FIG. 3 is a fragmentary front view of the automobile tire, showing in enlargement the portion of 3—3 in FIG. 1; and, FIG. 4 is a cross-sectional view of the automobile tire, taken along line 4—4 and in the direction of arrows in FIG. 3. In the drawings, the broken lines depicting the tire sidewall and inner bead and the dash-dot-dash lines indicating the peripheral boundary of the claimed design form no part of the claim.
